UNITED STATES PATENT OFFICE.

EDWARD J. OWEN, OF MINERVA, OHIO, ASSIGNOR TO OWEN CHINA COMPANY, OF MINERVA, OHIO, A CORPORATION OF DELAWARE.

DESIGN FOR A PLATE.

No. 37,903.

Specification for Design.

Patented March 20, 1906.

Application filed October 26, 1905. Serial No. 284,580. Term of patent 7 years.

To all whom it may concern:

Be it known that I, EDWARD J. OWEN, of Minerva, Stark county, Ohio, have invented a new, original, and ornamental Design for Plates, reference being had to the accompanying drawing, forming part of this specification, which is a plan view of a plate embodying my design.

I claim—

The ornamental design for a plate, as shown.

EDWARD J. OWEN.
